UNIVERSAL MOTOR SHELL

Gary G. Bluemink, Racine, Wis., assignor, by mesne assignments, to MSL Industries, Inc., Racine, Wis., a corporation of Minnesota

Filed Sept. 10, 1965, Ser. No. 86,939

Term of patent 14 years

(Cl. D26—5)

FIG. 1 is a view in three-quarters perspective showing the commutator end of a universal motor shell embodying my new design.

FIG. 2 is a view in three-quarters perspective showing the armature shaft end thereof.

FIG. 3 is a view thereof in side elevation.

FIG. 4 is a view in end elevation of the commutator end thereof.

FIG. 5 is a view in end elevation of the armature shaft end thereof.

FIG. 6 is a view taken in section through one end cap on the line 6—6 of FIG. 4.

FIG. 7 is a view taken in section through the opposite end cap on line 7—7 of FIG. 5.

The design features the contrasting effect which results from a shell in which a central sheet metal band joins die cast end caps which are distinctively formed as shown.

I claim:

The ornamental design for a universal motor shell, as shown and described.
